ELECTRICAL AMPLIFIER

Frederick W. Cunningham, Brooklyn, N. Y., assignor to Arma Corporation, Brooklyn, N. Y., a corporation of New York

Application April 12, 1944, Serial No. 530,589

6 Claims. (Cl. 179—171)

1

This invention relates generally to electric amplifiers, has particular reference to booster type electronic tube amplifier units, and is especially adapted for supplying power to a low impedance load varying with a signal component which is available from a high impedance source, which source cannot of itself supply the electric power for energizing such load without being undesirably affected by the load.

Ordinarily, if a voltage from a high impedance source is applied to a low impedance load, the phase and magnitude of the supply voltage from the high impedance source are altered. In signalling where accurate signal transmission is required, as in computing apparatus, the result of such variations in phase and magnitude creates a source of error which must be compensated, but exact compensation is frequently difficult to attain in cases where signal voltages vary widely and rapidly. If the voltage applied to a low impedance load could be balanced against the supply voltage from a high impedance source so that they have the same phase and magnitude at all times, the desirable operating characteristics of an amplifier for accurate signalling purposes would be attained, and it is the principal object of this invention to provide such amplifiers.

The invention comprises a "semi-direct" coupled electronic booster amplifier employing one hundred per cent inverse voltage feed-back, in which the signal voltage is amplified in an initial stage, supplied to a phase inverter through resistance coupling producing two signals 180° out of phase, which are fed through the aforementioned semi-direct coupling to a push-pull amplifier stage whose output is impressed upon the primary winding of an output transformer, whose secondary voltage is fed back to the input grid of the first stage to effect inverse voltage feed-back. Inverse voltage feed-back in the power output stage is employed to lower the output impedance of the amplifier by reducing the plate impedance of the last stage tubes, and high frequency oscillation is avoided by the use of condensers, principally in the output transformer primary circuit, whereas the hum level with zero signal is kept low by the use of filter networks in the initial amplifier stages.

By means of the amplifier of this invention the voltage applied to a low impedance load is of the same phase and magnitude as the supply voltage from a high impedance source and hence accurate amplifications of signals is possible, even under a wide signal voltage range of two hundred to one, an accuracy of better than $\pm 0.1\%$ having

2

been obtained with the new amplifier. Also, high frequency oscillation has been eliminated for wide limits of load in the amplifier, which is also devoid of low frequency oscillation or "bounce" and still tolerates a high source impedance without becoming unstable. Other advantages will become apparent from the following description of the preferred construction of the amplifier and its field of use, taken in connection with the accompanying drawings, in which:

Figure 1 is a circuit diagram of the amplifier unit of this invention; and

Fig. 2 is a schematic diagram illustrating a method of application of the amplifier of this invention.

Referring to Fig. 1 of the drawings, the booster amplifier unit 8 comprises an input circuit 10 and an output circuit 12 having a single common lead or conductor 14. The amplifier unit 8 also includes a pair of twin triode space discharge devices or tubes 16 and 18, such as of the 6SC7 type, a pair of beam power space discharge devices or tubes 20, such as of the 6V6 type, and a dual-secondary transformer 24. The tubes 16—20 have cathode heating elements 26 provided with input terminals which are connected respectively to any suitable electric supply source, not shown.

A suitable source of plate voltage, not shown, having a positive terminal B+, is connected between the respective anode or plate circuits of the four tubes, and a common negative conductor or ground. The plates 30 and 32 of the twin triode tube 16 are connected to the positive terminal B+ through a common circuit 34 including filter network resistors 36, 38 and 40 and divided circuits 42 and 44 including resistors 46 and 48, respectively. The plate 58 of the twin triode tube 18 is connected to the terminal B+ through an anode circuit 52 including a resistor 54, conductor 56, and the resistors 38 and 40. The other plate 50 of the tube 18 is likewise connected to the terminal B+ through an anode circuit 60 including a resistor 62, the conductor 56, and resistors 38 and 40.

The plates 62 of the beam power tubes 20 are connected through conductors 66, 66, respectively, to opposite terminals of the primary winding 10 of the transformer 24, the winding 70 having a center tap 68 connected to the positive plate voltage supply terminal B+ by a conductor 72.

The twin triode 16 is used as the first amplifier stage in the amplifier unit 8. The control grid 74 of such triode is connected to a signal supply circuit through a lead 76 provided with 55 a shield 77, which may be grounded through a

suitable resistance, or as is shown, connected by a conductor 78 to the common input-output lead 14, which is grounded through a high resistor 79 across the output winding 79 of transformer 24. Capacitance between the input grid circuit 76 and ground is thus avoided. If not avoided, such capacitance would be the cause of high frequency oscillation, which is highly undesirable. The other grid 80 of the twin triode 16 is connected directly to ground through lead 81. The common cathode 82 of twin triode 16 is connected to ground through a suitable cathode resistor 83.

The filter network, comprising resistors 36, 38 and 40, also includes suitable condensers 84, 86 and 88 connected between the common circuit 34 and ground, the arrangement being such that such filter network functions, in the plate circuits of the twin triodes 16 and 18, to maintain a low hum level with zero signal. No filtering is needed in the push-pull power output stage.

The control grid 100 of twin triode 18 is connected to the output circuit 44 of twin triode 16 through an input circuit 102 containing a condenser 104, the grid 100 being connected to ground through a resistor 106. The common cathode 108 of such tube 18 is likewise connected to ground through a resistor 110. The output plate 58 of the first triode amplifier stage of the tube 18 is connected through a condenser 114 to resistors 116 and 118, the control grid 120 of the second triode of tube 18 being connected by a lead 122 to the same at a point between the resistors 116 and 118. The tube 18 thus acts as a phase inverter by virtue of such resistance coupling. For balanced push-pull operation of the amplifier, the resistance value of resistor 118 should be equal to the sum of the resistance values of resistors 116 and 118 divided by the gain of the first triode of the twin triode 18. Two amplified signals 180° out of phase are thus obtained in the output circuits 52 and 60.

The output circuits 52 and 60 are coupled to the input circuits 124 and 126 of the beam power tubes 20 according to the invention by novel "semi-direct" couplings, each including a coupling condenser 128 and a resistor 130 shunted across such condenser 128. Such semi-direct coupling 128, 130, among other advantages, minimizes low frequency oscillation.

Balancing resistors 132 and 134 are connected between the input circuits 124 and 126, respectively, and ground. A series circuit containing a resistor 136 and a condenser 138 is connected from the input circuit 124 to ground. The impedance values of resistor 136 and condenser 138 are such as to cause a reduction in the gain for relatively high signal frequency values without phase shifting of the translated signal, in the same manner as the semi-direct coupling 130, 132 functions at relatively low values of signal frequency.

The beam power tubes 20, 20 are connected in push-pull relation, the control electrodes or grids 140 of such tubes being connected to the input leads 124 and 126. The anodes 62 are connected to opposite terminals of the transformer primary 70 through conductors 66, as pointed out above, while the cathodes 145, 146 are connected through conductors 148, 148 containing resistors 150, 150 to opposite terminals of the transformer secondary winding 151. The secondary winding 151 is provided with a center tap which is grounded through a resistor 152.

A circuit 154 containing condensers 156 and 75

158 is connected across the primary winding 70 of the transformer 24 for the purpose of avoiding high frequency oscillation with the screen grids 160, 160 of the tubes 20 connected to a conductor 162 which is connected between the circuit 154 and the circuit 72, which supplies the screen grids 160 with the full B+ voltage direct from the source.

The secondary winding 164 of the transformer 10 is included in the output circuit 12 of the amplifier unit 8, and the output voltage from such winding is fed back to the grid 74 of the twin triode 16, 180° out of phase with the input required voltage. The booster amplifier unit 8 employs 100% inverse voltage feed-back.

In considering the operation of the amplifier unit 8, a signal voltage Vs is impressed on the grid 74 of twin triode 11 where it is amplified. In order to get maximum gain at this point a unique hook-up of the twin triode 16 is used. The entering signal on the grid 74 causes current to flow between cathode 82 and plate 30, and since cathode 82 is connected to ground not directly but through a resistance 83, grid bias is developed proportional to the signal. But this resistor 83 unfortunately also acts to reduce the gain of the tube. For this reason the other triode of the twin triode is brought into play. Here, the grid voltage being always zero (due to grid 80 being directly grounded) the effect of the cathode voltage swing is to decrease current flow in the "robber" circuit 42 and thereby increase current in the main circuit 44. By this novel means the degeneration due to the cathode resistance 83 is neutralized and the fullest possible gain of the triode 82, 74, 30 is secured.

The amplified output of tube 16 is next fed into twin triode 18, which acts as phase inverter through resistance coupling 116—118. The resistance values of the resistors 116, 118 are such that balanced push-pull operation of the amplifier is obtained. The two signal components, which are 180° out of phase, are fed through the semi-direct coupling 128, 130 to the control grids 140 of the beam power amplifier tubes 20 which are connected in push-pull relation. The semi-direct coupling consisting of resistors 130 shunted across coupling condensers 128, minimizes low frequency oscillation.

If at a given signal frequency the combined phase shift of an amplifier and feed-back circuit is 180° or greater, the product of the amplifier gain and the vectorial transmission between the output and input circuits should be less than unity, since, if otherwise, the resultant reversal of phase might supply sufficient output voltage to sustain oscillations begun by some perturbation of the loop. This trouble is overcome according to the present invention in which semi-direct coupling is employed between successive amplifier stages of the amplifier unit. Such semi-direct coupling functions to maintain to a minimum value the phase shift at very low frequency values of the signal due to coupling without appreciably affecting the magnitude of the output voltage. Stability for such frequencies is obtained by keeping the total phase shift of the amplifier to less than 180° for low frequencies. Compared to direct-coupling, the advantage of semi-direct coupling includes a loss of gain at low frequencies that makes it easier to get the overall drop in gain that is required for stability at low frequencies, and much less dependence on tube characteristics. Compared to resistance-capacity coupling, the big advantage of semi-direct cou-

pling is the decided decrease in phase shift at low frequencies, without appreciably affecting the phase shift or magnitude of the translated signal component at higher frequencies.

The output of the push-pull power stage is fed into the primary 70 of the output transformer 24. Inverse voltage feed-back is accomplished by feeding the output voltage from the secondary 164 of transformer 24 back to the grid 74 of twin triode 16. The inverse voltage feed-back in the power output is accomplished by feeding the voltage from secondary 151 of the transformer 24 to the cathodes 146 of the beam power amplifier tubes 20. The beneficial effects of feed-back are:

1. Reduction of harmonic distortion.
2. Greater stability, including constance of characteristics with changes in tubes or input voltage V_s .
3. Reduction of phase distortion.
4. Reduction of hum level.
5. Reduction in the internal impedance of the amplifier.

This last factor is important in that the output impedance of the amplifier is kept to a minimum.

The following advantages have been derived in booster amplifier unit 8:

1. Freedom from "bounce" or low frequency oscillation.
2. High frequency oscillation has been eliminated for wide limits of load.
3. A high source impedance can be tolerated.
4. The hum level is less than 0.004% of the maximum full signal input voltage.

High frequency oscillation is avoided by condensers 156 and 158 across the output transformer primary 70 and by a condenser 138 in series with a resistor 136 on the input 124 of the third stage. The values of resistor 136 and condenser 138 are such as to cause a reduction in the gain for high frequencies without shifting the phase, in the same manner as the semi-direct coupling effect on low frequencies.

Although a high source impedance can be tolerated, care must be observed to avoid capacitance from the input grid circuit to ground, thereby causing high frequency oscillation. This is readily taken care of by connecting the input circuit shield 71 to ground through a suitable resistance or by connecting the shield 71 to the input-output common lead 14 with conductor 78.

The hum level with zero signal is kept low by proper filter networks in the plate circuits of twin triodes 16 and 18, comprising resistors 36, 38, 40 and condensers 84, 86, 88. No filtering is needed in the push-pull power output stage 60.

This booster amplifier 8 operates over a signal voltage range of 200 to 1 with an accuracy of better than $\pm 0.1\%$.

Such a booster amplifier unit 8 may be used in conjunction with a resolver 168. In the application of an electrical resolver, which is illustrated and described in detail in copending application Serial No. 346,183, filed July 18, 1940, it is highly desirable that the phase of the secondary voltage and its magnitude when set at the maximum position be the same as those of the signal voltage. It is clear that if the primary impedance of the resolver were constant a simple phase shifting network might be employed between the booster amplifier and the resolver to correct its phase. However, the resolver has a ferro-magnetic core and its main circuit resistance is a function of the flux density and so of the applied voltage. For this reason, a com-

pensator 170 is used as shown in Fig. 2. The leakage reactance of the resolver is due principally to flux which has a long path in air, and the leakage resistance is due to the copper winding. The ratio of reactance to resistance of the compensator primary 172 and resistor 174 is made the same as the ratio of reactance to resistance of the leakage impedance of the resolver. Then, since the same current flows through both of these impedances the voltage across the primary coil 172 of the compensator will be proportional to the loss of voltage in the leakage impedance.

The turns ratio of secondary 176 which is closely coupled to the primary 172, to that coil 15 is made such that the voltage across the secondary 176 is equal to the voltage across the leakage impedance of the resolver. This voltage is then introduced into the input of the booster amplifier unit 8 in the direction required to neutralize the leakage impedance of the resolver 168. If freedom from temperature effects is required the resistor 174 should be made of copper.

It is possible to vary the ratio of input signal voltage V_s to output signal voltage V_o , or the effective transformation ratio of the resolver 168 when used in conjunction with the booster amplifier unit 8 and compensator 170, by means of a shunt resistor 178. If the resistance value of resistor 178, or leakage resistance, is decreased, 30 by shunting with the resistor 174 the ratio V_o/V_s is increased, as will the ratio V_o/V_s .

Although a preferred embodiment of the invention and one use thereof are illustrated and described herein, it is to be understood that the invention is not limited thereto, but the invention is susceptible of various uses as well as changes in form and detail within the scope of the appended claims.

I claim:

40. The combination with a signal supply circuit having a relatively high value of effective impedance, and a load circuit having a relatively low value of effective impedance, of an amplifier circuit responsive to a signal component derived from said signal supply circuit comprising a twin triode amplifier tube, one of said triodes thereof increasing the gain of the other triode, for applying a similar component of substantially the same phase and magnitude as such signal component to said load circuit.
45. The combination with a signal supply circuit having a relatively high value of effective impedance, and a load circuit having a relatively low value of effective impedance, of an amplifier circuit responsive to a signal component derived from said signal supply circuit comprising a twin triode amplifier tube, one of said triodes thereof increasing the gain of the other triode, for applying a similar component of substantially the same phase and magnitude as such signal component to said load circuit.
50. The combination with a signal supply circuit having a relatively high value of effective impedance, and a load circuit having a relatively low value of effective impedance, of an amplifier circuit responsive to a signal component derived from said signal supply circuit comprising a twin triode amplifier tube, one of said triodes thereof increasing the gain of the other triode, for applying a similar component of substantially the same phase and magnitude as such signal component to said load circuit.
55. The combination with a signal supply circuit having a relatively high value of effective impedance, and a load circuit having a relatively low value of effective impedance, of an amplifier circuit responsive to a signal component derived from said signal supply circuit comprising a twin triode amplifier tube, one of said triodes thereof increasing the gain of the other triode, for applying a similar component of substantially the same phase and magnitude as such signal component to said load circuit.
60. The combination with a signal supply circuit having a relatively high value of effective impedance, and a load circuit having a relatively low value of effective impedance, of an amplifier circuit responsive to a signal component derived from said signal supply circuit comprising a twin triode amplifier tube, one of said triodes thereof increasing the gain of the other triode, for applying a similar component of substantially the same phase and magnitude as such signal component to said load circuit.
65. The combination with a signal supply circuit having a relatively high value of effective impedance, and a load circuit having a relatively low value of effective impedance, of an amplifier circuit responsive to a signal component derived from said signal supply circuit for applying a similar component of substantially the same phase and magnitude as such signal component
70. The combination with a signal supply circuit having a relatively high value of effective impedance, and a load circuit having a relatively low value of effective impedance, of an amplifier circuit responsive to a signal component derived from said signal supply circuit for applying a similar component of substantially the same phase and magnitude as such signal component

to said load circuit, said amplifier circuit comprising electronic means adapted to amplify such signal component, a phase inverter circuit responsive to such amplified signal component for producing two signal components which are 180° out of phase with each other, a pair of power amplifier space discharge devices connected in push-pull relation, and semi-direct means coupling the output circuits of said phase inverter circuit to the input circuits of said power amplifier space discharge devices.

4. The combination with a signal supply circuit having a relatively high value of effective impedance, and a load circuit having a relatively low value of effective impedance, of an amplifier circuit responsive to a signal component derived from said signal supply circuit for applying a similar component of substantially the same phase and magnitude as such signal component to said load circuit, said amplifier circuit comprising electronic means adapted to amplify such signal component, a phase inverter circuit responsive to such amplified signal component for producing two signal components which are 180° out of phase with each other, a pair of power amplifier space discharge devices connected in push-pull relation, and semi-direct means coupling the output circuits of said phase inverter circuit to the input circuits of said power amplifier space discharge devices, said semi-direct coupling means comprising a coupling condenser between said input and output circuits, and resistors in shunt circuit relation with said coupling condensers, for minimizing low frequency oscillation in the amplifier circuit.

5. In combination, a relatively high impedance signal supply circuit, an untuned current amplifier circuit the input circuit of which is coupled to said signal supply circuit, and a relatively low impedance load circuit coupled to the output circuit of said untuned current amplifier circuit, said untuned amplifier circuit including an am-

- plifier, a phase inverter, a pair of space discharge devices connected in push-pull circuit relation, and a semi-direct coupling between said amplifier and phase inverter, respectively, and said space discharge devices, said coupling consisting of condensers in series with the control grids of said space discharge devices and the output circuits of said amplifier and phase inverter, and resistors connected across said condensers, whereby said untuned current amplifier circuit is adapted to apply to said load circuit a voltage component of substantially the same phase and magnitude as that received by its input circuit from said original supply circuit.
- 10 6. In a 100% inverse feed-back booster amplifier unit of the class described, a plurality of amplifier stages comprising electronic tubes, at least two amplifier tubes of which are connected in push-pull relation, and semi-direct coupling means between the input circuits of such tubes and the output circuits of the preceding stage, consisting of capacitance and resistance in parallel, the impedance values of which are proportioned so as to inhibit inherent phase displacement due to a change of frequency of a signal component translated by the unit.
